UNITED STATES PATENT OFFICE.

GEORGE P. BOSWORTH, OF CENTRAL FALLS, RHODE ISLAND, ASSIGNOR TO HEMPHILL MANUFACTURING CO., OF PAWTUCKET, RHODE ISLAND.

STOCKING-KNITTING MACHINE

1,204,397.

Specification of Letters Patent. Patented Nov. 14, 1916.

Application filed April 11, 1914. Serial No. 831,296.

To all whom it may concern:

Be it known that I, GEORGE P. BOSWORTH, citizen of the United States, residing at Central Falls, Rhode Island, have invented 5 certain new and useful Improvements in Stocking-Knitting Machines, of which the following is a specification.

My invention relates to circular knitting machines of the type designed to narrow 10 and widen the fabric, for instance in making heels and toes of stockings, and one object of my invention is to provide a machine in which the widening operation can be continued beyond the point where widening 15 ceases in present practice. A result flowing from a machine capacitated to accomplish this result is that an additional number of courses of knitting may be thrown in between the heel gore and the foot after 20 completing the usual form of heel pocket, thus giving to the stocking a longer sole than instep, tending to make the foot assume a position nearer to a right angle than is customary in seamless stockings, and 25 giving rise to other advantages hereinafter pointed out.

It is usual in circular knitting machines for making seamless stockings to employ 30 a half circle of short butt heel and toe needles, and a half circle of long butt instep needles, and to make the long butt instep needles inoperative in an elevated position while picking is done on the short butt needles for making the heel and toe. 35 It has not been found practical heretofore to continue picking on the instep needles, and the widening actions were therefore necessarily limited to a number of needles less than the half circle of short butts. In 40 carrying out my invention, however, I provide a way of continuing the picking during the widening process beyond the point where the usual form of heel pocket is produced, with the result that the form of 45 stocking above mentioned may be knit.

The invention consists in the features and combination and arrangement of parts hereinafter described and particularly pointed out in the claims.

50 While my invention may be carried out in connection with machines of various makes, in the particular form chosen to illustrate my invention it is shown in connection with

the Banner type of machine made under Letters Patent of the United States #933,443, 55 granted to J. D. Hemphill, September 7, 1909.

In the drawings Figure 1 is a diagrammatic view of the usual form of stocking showing the heel gore; Fig. 2 is a view of a 60 stocking produced on my improved machine having the heel gore and the additional widenings between the same and the foot; Fig. 3 is a front view of a knitting head embodying my improvements; Fig. 4 is a 65 front view of part of Fig. 3; Fig. 5 is a front view in outline of the knitting head, said view showing certain driving and controlling mechanism like that of the "Banner" machine; Fig. 6 is a diagrammatic development of the cam ring needles and jacks; Fig. 7 is a plan view of the cam ring and 70 its support; Fig. 8 is a sectional view of the needle cylinder wall showing the jacks, needles, and the instep lowering cam; Fig. 75 9 is a view similar to Fig. 8 showing the jacks, needles and the ordinary instep cam for use when some of the needles of the instep series are provided with long butts; Fig. 10 is a view of the ordinary instep 80 cams of Fig. 9 with their operating mechanism; Fig. 11 is a view of a detail.

In carrying out my invention all the needles throughout the entire needle circle may be short-butt needles, or all of the heel 85 and toe needles, together with some of the instep needles, may be short butt, the remaining needles of the instep series having long-butts, as in ordinary practice.

I will first refer to a machine having a 90 short-butts throughout the entire needle circle. It may be noted here that while the term "short-butt" is a relative one ordinarily involving comparison with a butt of greater length, yet for convenience I employ this 95 term in referring to that embodiment of my invention first mentioned, in which all the needles of the entire circle have substantially the same length of butt because in the art the heel and toe needles are ordinarily referred 100 to as short butt needles, and in my invention needles of this same character in whole or in part make up the instep series.

In the drawings the needle cylinder 1, the stitch cams 2, the guard cam 3, narrowing 105 picks 4, widening picks 5, instep restoring

cam 6, its vertically adjustable block 7, the bell crank lever 8, operating connection 9, and other parts hereinafter referred to are substantially of the same form and arrangement as on the "Banner" machine.

Referring to all the drawings excepting Figs. 9 and 10: The short-butt needles are indicated at *a*, Fig. 8, and in the form of machine now being described these would compose the entire needle circle.

The lower instep cam ordinarily employed for elevating the instep needles to inoperative position is omitted, this in usual practice being attached to the vertically adjustable block 7 to be elevated when the machine goes on reciprocating knitting, for the heel and toe. Instead of this cam I employ jacks for raising the instep needles to render them inoperative when the heel and toe is to be formed, these jacks 10 having butts engaging the cam groove 11 formed on the inner face of the cam ring, and for operating these jacks to raise the instep needles a pivoted switch cam 12 is employed mounted within a recess or cut-out portion of the cam ring and pivoted at 13. This cam is shown in its lowest position in Figs. 3 and 4, and in full lines in Fig. 6. When in this position the jacks ride over this cam, but are not raised far enough to elevate the needles. The jacks in the form of machine now being described are under one-half the needles, these being the instep needles. When the switch cam is raised to the dotted line position of Fig. 6, the jacks will be raised, and in turn will raise the instep needles, it being understood that the instep jack cam 12 is raised when the jacks and instep needles are on the opposite side of the needle circle from that on which the jack cam is located. At the same time the restoring cam 6 of the usual instep set is also raised.

When raised by the jacks the instep needles have their butts in position to engage and pass over the A shaped cam 14, which is fixed to the usual cam supporting plate H of the Hemphill machine, and upon being elevated by this fixed cam the instep needles are in inoperative position, for it will be noticed that they will then pass over the picks, the stitch cams 2 and the guard cam 3, and they will remain in this position. All the instep needles having been elevated as just described, the formation of the heel pocket by narrowing and widening will go on by the picks, the narrowing picks first acting to pick the heel and toe needles upwardly to inoperative position, as in ordinary practice first at one end of the column of active heel and toe needles, and then at the other end and until narrowing has proceeded to the proper point when the widening picks are brought into action and widening of the fabric for the heel pocket takes place by picking down into operation a heel and toe needle

first from one end of the column of inactive needles and then from the other end.

With the form of machine used heretofore, picking for widening would cease when the last of the heel and toe needles had been brought down into operative position, because heretofore picking of the instep needles for additional widenings has not been practical owing to these instep needles having long butts, but in my present machine the picking for widening the fabric can be continued after the widenings for the heel pocket have been performed, because picking by the widening picks can continue on the short butt needles of the instep series after the heel gore has been formed, these instep needles having substantially the same length butts as the heel and toe needles, and thus the additional widening course represented by the line *x* in Fig. 2 will be produced giving the stocking certain advantages already touched upon. For continuing this picking for widening after the widenings for the heel pocket have been made, it will be necessary to maintain the machine on its reciprocating movement after the widening has been effected to the point where narrowing began, and likewise to continue the widening pick mechanism in operation, and to hold the upper restoring cam 6 in its elevated position to avoid lowering the inoperative needles. After the additional widening courses have been made, the machine goes on round knitting, as in ordinary practice, by throwing the widening pick mechanism out of operation, by changing the movement of the machine from reciprocating to rotation in one direction, and by lowering the instep needle cam 6, it being understood that the jack switch cam also has been lowered, this taking place if desired as soon as all the jacks have been elevated to their full limit thereby.

It is not necessary to have a half circle of jacks and a full circle of short butt needles, as it is necessary to have only as many short butt needles in the instep series with their co-operating jacks as is required to widen the fabric for the heel pocket widenings and continue beyond the point where narrowing began. In other words, the instep series of needles may be composed in part of short butt needles, and in part of long butt needles, in which event the short butt needles of this instep series would be elevated to inoperative position by the jacks while the long butt needles of this instep series would be elevated to inoperative position by the usual instep cam shown at 16 in Figs. 9 and 10, and by these two elevating means all the instep needles would be elevated to their inoperative position the same as though they were all long butt needles as in usual practice, and the picking for widening could be continued on the instep

needles up to the end of the column of the short butt needles of this series.

The cam 16 is attached as in usual practice to the vertically adjustable block 7 to move with the cam 6. These cams are elevated to render the instep needles inoperative, or when only the upper cam 6 is employed this cam is raised and lowered, by the link 9 connected with the motion changing lever *b'* which is common in the "Banner" machine. This lever is pivoted at 18 to the frame, and its lower end is controlled by the pattern drum 19. It operates a clutch member 20 to drive the machine either 13 through the gearing 21 for round knitting or through the quadrant 22 and gear 23 for reciprocating knitting. The machine as represented in Fig. 5 is set for round knitting, the lever *b'* being swung to the right at its 20 upper end to make the clutch drive from the gearing 21. The restoring or lowering cam 6 for the instep needles as shown in Fig. 6 is down, the connection 9 and bell crank lever 8 having been operated to so position 25 this cam, or if both instep cams 6 and 16 are used, *i.e.*, with a few long-butt instep needles, both of these cams would be down. The jack operating switch cam 12 would also be down. This cam is mounted on the shaft 30 18 to turn therewith, said shaft being journaled in the cam supporting plate H and having an arm 24 fixed to its outer end connected by link 25, lever 26, and link 27 to a lever 28 pivoted to the frame and operated 35 by projections 29 of the pattern mechanism, and by a spring 28'.

The quadrant gear 22 will, of course, be of proper length to give the desired length of stroke of the machine on reciprocating 40 work, for instance slightly more than a full revolution. The desired length of stroke can be secured in other ways. The pattern drum 19 is substantially the same as in the "Banner" machine, it having pattern blocks, recesses, etc., for controlling the various 45 functions of the machine. This pattern drum is operated step by step by a pawl and a coarse tooth ratchet, the latter being indicated at *e* and correspondingly to the similarly marked part of the Hemphill patent. This ratchet is fixed to the shaft of the 50 pattern cylinder or drum and the engagement of the pawl with the ratchet is determined by a controller *h* like that of said 55 patent, which, in turn, is controlled by lugs on a pattern chain B. This chain derives its step by step movement from a fine toothed ratchet operated as in the Hemphill patent. The maintenance of the reciprocations of 60 the needle cylinder beyond the point where widening for the heel pocket ceases is controlled from the pattern chain. Ordinarily there is an equal number of links for narrowing and widening, say, for instance, nine 65 for narrowing and nine for widening, but

with my improvement we have, for instance, nine links for narrowing and more for widening.

The stocking referred to as illustrating the character of work of which my invention is capable is what is known to the trade as the Hirner fashioned foot stocking, this being a seamless stocking having heel and toe pockets corresponding to the usual heel and toe pockets of seamless stockings but 70 having interposed between the heel gore and the foot a certain number of additional widening courses of knitting, two courses of knitting in this part of the stocking to one wale in the ankle, which merges with them. 75 As above stated, this gives to the stocking a longer sole than instep, and positions the foot more nearly at a right angle to the leg than is the case with a stocking formed in the usual way by terminating the widening 80 at the same point where the narrowings began in the formation of the heel pocket. The new construction of stocking also gives a greater width from the instep to the point 85 of the heel.

Where in the appended claims I refer to elevating instep needles to inoperative position by jacks, I mean that these needles either in whole or in part are acted on by these jacks, the preceding description making it clear that some of the instep needles 90 may have long butts to be raised by the ordinary instep cam, as in ordinary practice.

I claim as my invention:—

1. In combination in a stocking knitting 100 machine, narrowing and widening pick mechanism, heel and toe and instep needles, having substantially the same length of butts, means including a lifting cam for making instep needles inoperative as a group 105 in beginning the formation of the heel, said widening pick mechanism continuing its operation upon the group of instep needles as raised by said cam after widening for the heel pocket has been completed to make additional widening courses, substantially as described.

2. In combination in a circular stocking knitting machine, short butt needles for making the heel and toe pockets, and short 110 butt instep needles, and narrowing and widening pick mechanism, said widening pick mechanism operating upon the heel needles to widen for the heel pocket and continuing its operation upon the short butt instep 115 needles after the widening for the heel pocket has been performed to thereby throw in additional widening courses previous to resuming round knitting, substantially as described.

3. In combination in a circular knitting machine for making stockings, heel and toe needles, instep needles, jacks for elevating the desired number of instep needles as a group to render them inoperative, a cam for 120 125 130

operating the jacks, means for operating the jack cam, narrowing pick mechanism and widening pick mechanism operating upon the heel and toe needles, and continuing the 5 picking operation upon the instep needles which were initially elevated as a group by the jacks after the widening for the heel pocket has been completed.

4. In combination in a stocking knitting 10 machine, a needle cylinder, heel and toe and instep needles, knitting cams, a vertically movable needle restoring cam to engage the instep needle butts for lowering them to operative position, automatically operating 15 connections for moving said needle restoring cam vertically to different positions, an automatically operated vertically movable needle raising cam for raising instep needles, and narrowing and widening pick 20 mechanism, said last mentioned cam being pivotally mounted to swing in a vertical plane, said widening pick mechanism continuing the widenings beyond the point where narrowing began and connections 25 automatically operating independently of the first mentioned connections for operating the needle raising cam and lowering it before the continued widening of the fabric takes place, substantially as described.

30 5. In combination in a stocking knitting machine, a needle cylinder, heel and toe and instep needles, knitting cams, a vertically movable needle restoring cam to engage the instep needle butts for lowering them to operative position, automatically operating 35 connections for moving said needle lowering cam vertically to different positions, an automatically operated vertically movable cam for raising instep needles, narrowing and 40 widening pick mechanism, and jacks under the instep needles and operated by said last mentioned cam, said widening pick mechanism continuing the widenings beyond the point where narrowing began and connections 45 automatically operating independently of the first mentioned connections for operating the needle raising cam and lowering it before the continued widening of the fabric takes place, substantially as described.

50 6. In combination in a circular stocking machine, a rotary and reciprocatory needle cylinder, narrowing and widening pick mechanism, a vertically sliding restoring cam for the needles, a vertically swinging 55 cam for elevating the needles, a rock shaft carrying said cam, a change motion lever

for changing the movement of the needle cylinder from rotary to reciprocating movement, connections for sliding the instep cam, said widening pick mechanism continuing the widenings beyond the point where narrowing began, and a second set of connections operating independently of the connections first mentioned for rocking the shaft carrying the needle elevating cam, said 60 cam being lowered to normal position before the continued widenings begin, substantially as described.

7. In combination in a stocking knitting machine of the type having a rotary needle 70 cylinder and a non-rotary cam ring, knitting cams, heel and toe and instep needles, narrowing and widening pick mechanism, a vertically adjustable plate carrying the knitting cams and varying their position relative 75 to the needles according to its adjustment, a post mounted on said plate, a vertically adjustable needle restoring cam slidably mounted in said post, a cam pivotally mounted on said plate to swing vertically for adjusting 80 the instep needles toward inoperative position, and connections for operating the pivoted cam and sliding the restoring cam, independently of each other, said widening pick mechanism continuing its actions beyond the point where narrowing began, and 85 said pivoted cam returning to normal position before the continued widenings begin, substantially as described.

8. In combination in a stocking knitting 90 machine of the type having a rotary needle cylinder and a non-rotary cam ring, knitting cams, heel and toe and instep needles, a vertically adjustable plate carrying the knitting cams and varying their position relative 95 to the needles according to its adjustment, a post mounted on said plate, a vertically adjustable needle restoring cam slidably mounted in said post, a cam pivotally mounted on said plate to swing vertically for 100 adjusting the instep needles toward inoperative position, connections for operating the pivoted cam and sliding the restoring cam, and jacks carried by the cam ring to be operated by said pivoted cam, substantially 105 as described.

In testimony whereof, I affix my signature in presence of two witnesses.

GEORGE P. BOSWORTH.

Witnesses:

JAMES L. JENKS,
JOHN LAWSON.
